US0D1043894S

(12) **United States Design Patent** (10) **Patent No.:** **US D1,043,894 S**
(45) **Date of Patent:** **** Sep. 24, 2024**

(54) **PROJECTILE**

- (71) Applicant: **G9 Holdings, LLC**, Lakewood, CO (US)
(72) Inventor: **Joshua Mahnke**, Post Falls, ID (US)
(73) Assignee: **G9 HOLDINGS, LLC**, Lakewood, CO (US)
(***) Term: **15 Years**
(21) Appl. No.: **29/773,212**
(22) Filed: **Mar. 8, 2021**

Related U.S. Application Data

- (60) Division of application No. 29/709,402, filed on Oct. 14, 2019, now Pat. No. Des. 978,277, which is a division of application No. 29/590,952, filed on Jan. 13, 2017, now Pat. No. Des. 863,492, which is a continuation of application No. 14/701,519, filed on Apr. 30, 2015, now Pat. No. 9,709,368.

(57) **CLAIM**

The ornamental design for a projectile, as shown and described.

DESCRIPTION

FIG. 1 is a left perspective view of a projectile; FIG. 2 is a front elevation view thereof, which is a mirror image of the rear elevation view; FIG. 3 is a top plan view thereof, which is a mirror image of the bottom plan view; FIG. 4 is a right elevation view thereof; FIG. 5 is a left elevation view thereof; FIG. 6 is a left perspective view of a projectile according to an alternative embodiment, where the projectile is symmetrical around the longitudinal axis when split into fifths and the projectile includes a repeating pattern of cutouts; FIG. 7 is a front elevation view of the projectile of FIG. 6, which is a mirror image of the rear elevation view; FIG. 8 is a top plan view of the projectile of FIG. 6; FIG. 9 is a bottom plan view of the projectile of FIG. 6; FIG. 10 is a right elevation view of the projectile of FIG. 6; and, FIG. 11 is a left elevation view of the projectile of FIG. 6.
